SAFETY SWITCH AND FUSE BOX

William M. Mitchell, Brooklyn, N. Y., assignor of
one-half to John H. Schwab, New York, N. Y.

Application March 29, 1934, Serial No. 718,616

3 Claims. (Cl. 200--114)

This invention relates to switches and fuse boxes and particularly to an improved safety switch and fuse box, the object being to provide a construction which is to be used with a meter in dwellings or other houses where the electric current is to be paid for at a certain rate.

Another object of the invention is to provide a switch and fuse box which is interposed between the main supply line and the meter where the meter is distributing current to the place of use, the structure being such that all parts of the wire leading from the supply buses to the meter are covered.

An additional object of the present invention is to provide a combined switch and fuse box wherein the desired number of fuses are interposed in a circuit, and wherein these fuses are mounted on a rotatable switch member, whereby when the switch member is in one position current will flow through the fuses, and when in another position current is turned off from the fuses and the circuit remains open.

Referring to the accompanying drawings—

Figure 1 is an elevation showing a meter, a combined switch and fuse box embodying the invention, and certain associated parts including the feed bus wires which feed the current to the meter;

Figure 2 is a front view of the combined switch and fuse box shown in Figure 1, the front plate being removed so as to illustrate the position of the wiring leading to the fuse box;

Figure 3 is a section through Figure 6 approximately on the line 3—3;

Figure 4 is a transverse sectional view through Figure 1 on the line 4—4, the same being on an enlarged scale;

Figure 5 is a view similar to Figure 4 but showing a modified construction wherein the fuse boxes are arranged interiorly of the casing;

Figure 6 is a vertical sectional view through Figure 1 on the line 6—6, the same being on an enlarged scale;

Referring to the accompanying drawings by numeral, 1 indicates a supporting board which is adapted to be secured to a wall or other desired place. On this board the combined switch and fuse box 2 is mounted. The combined switch and fuse box is provided with an outside frame 3 on which the meter 4 is provided, said meter being of any well known kind now in common use. In dwellings and elsewhere meters similar to the one shown in Figure 1 are used to measure the amount of current used by the consumer. Various forms of connecting wires have been used heretofore and are still being used for connecting the supply bus wires to the meter, and then the meter to the lights and other points where current is used. Any current passing through the meter will be measured and will be paid for. However,

in some instances unscrupulous persons have tapped the wires between the bus wires and the meter and have stolen current in this manner, particularly where large amounts of current is to be used, for instance, when it is desired to use an electric driven sanding machine for sanding floors. This practice naturally deprives the company supplying the electricity of proper return for their investment.

In the present invention the combined switch and fuse box has been provided to reduce to a minimum the chance of tapping the various wires to secure current in an unauthorized manner. The structure shown, for instance, in Figure 1 is such that when in one position current will flow through the meter to lamps or other points where current is used, but if the parts are turned to a second position current is turned off from the meter and consequently no current may be secured. This is done where a house is to be vacated or is vacant and it is desired to leave the meter in place.

As shown in Figure 1 the wires of the switch and fuse box are connected to supply bus wires 5 and 6 by suitable lead in wires 7 and 8 soldered or otherwise electrically connected with reciprocating contacts 9 and 10. It will be observed that the bus wires 5 and 6 are positioned in a protecting metal tube 11, and a tubular connection 12 protects the lead in wires 7 and 8 so that no one can possibly tap these wires and secure current in an unauthorized way. As all of the contacts 9 and 10 are identical a description of one will apply to all. As shown in Figure 3 the contact 10 is provided with a shoulder 13 which is acted on by a spring 15, which spring also acts on the retaining plate 14. This causes the large contact end 16 of the contact rod 10 to be urged inwardly continually and, consequently, will rest firmly on the outer surface 17 of the switch body 18. The contact 10 is arranged at the lower part of the device as shown in Figure 3, while a pair of similar contacts 19 are arranged at the upper part, said contacts 19 being connected by suitable wires in any desired manner to the meter 4 so that current passing through the meter will also pass through the wires 20 and 21 arranged in the cable 22. Wires 20 and 21 lead to the various outlets, for instance, lamps in the house in which the device is mounted. All current passing to the wires 20 and 21 passes through the meter and, consequently, will be paid for in the usual manner.

The various contacts 9 and 10, and also the contacts 19, are positioned to engage the contact plates 23, 24, 25 and 26, respectively, as shown in Figure 6. The contact plates 23 and 25 are in diametrically opposite sides of the switch body 18, and the plates 24 and 26 are also on diametrically opposite sides so as to engage the respective spring pressed contacts simultaneously. When the parts 60

are in the position shown in Figures 1, 2 and 6 all of the contacts are engaging their respective contact plates, but when the switch body 18 has been turned a short distance the parts may assume the position shown in Figure 3, whereupon all of the contacts are out of engagement with their contact plates and, consequently, the circuit is open so that no current will pass through the meter.

As illustrated in Figure 2 the wires 27 and 28 are connected to the respective contact plates 23 and 24 and to one of the terminals of the respective fuse boxes 29 and 30. Wires 31 and 32 are connected to the opposite terminal of the fuse boxes and to the respective plates 25 and 26. It will thus be seen that all current is passing in one direction through one fuse box and in the opposite direction through the other fuse box.

In order to prevent access to the wires 29 to 32 inclusive, there is provided a cover plate 33 and associated parts whereby no access can be had to the wires just mentioned and other parts until the lock 34 has been unlocked and the switch body 18 removed. After the lock 34 has been operated and the bolt 35 thereof retracted, the switch body 18 may be rotated, and as it is rotated in counter clockwise direction the retaining bolt 36 will be unscrewed through the threaded aperture 37. After this has been done the switch body may be easily removed and access had to any point.

It will be noted that the cover plate 33 is provided with internal threaded extensions 38 into which the screws 39 extend for clamping the plate 33 to the switch body. By removing these screws the plate 33 may be removed and access readily had to the wires 29 to 31, inclusive. The lock 34 may be of any well known kind but is preferably of the kind wherein the bolt 35 is pressed by the spring 40 so as to cause the same to snap into either of the two openings 41 and 42. When the bolt is in the opening 41 the parts are in operative position and current is allowed to flow, but when the switch body is rotated to the right, as shown in Figure 1, until the bolt 35 moves into the opening 42, current will not flow through the switch or the meter. The fuse boxes 29 and 30 may be the usual fuse boxes now in common use and may be connected in any desired way with wires 27, 28, 31 and 32 by screws or otherwise. These fuse boxes are arranged in suitable sockets in the switch body 18 as shown in Figure 4, so that the only part that will project beyond the cover 33 will be the metal covering rings on the ends of the fuse members.

By forming the various parts as described there is presented a switch whereby the company supplying the current may turn the same off and lock the parts so that no current can be turned on except by an authorized person. Also when the current is turned off there is absolutely no place where contact can be made with the supply wires 5 and 6. As shown in Figure 1, it will be noted that wire 43 is the usual ground wire and may or may not be used as preferred. When the parts are in operative position there is no place where current may be taken off except through the dispensing wires 20 and 21. It might be possible to remove the fuse members and screw plugs therein, but this would throw the whole load on the wires connected to the screw plugs and present a more or less dangerous construction, so that for practical purposes there are no

places whereby the supply wires may be tapped.

Referring to Figure 5 the same numerals will be used as in the preferred form except where the parts are modified. Figure 5 shows a construction similar to Figure 4 except that the fuse boxes 29' and 30' are arranged interiorly of the switch body 18. The various wires 27, 28, 30 and 32 are naturally on the opposite side of the body so that the covering plate 33' will have no openings therein except where the members 33 fit and where the lock 34 is positioned. It will therefore be seen that when this form of the invention is used there is absolutely no place where current may be taken from the switch or supply wires except through the meter 4. In the construction shown in Figure 1 all parts are protected except where the fuse boxes are positioned, thus making it somewhat difficult to steal electricity and yet have the various lamps and other electrical devices properly supplied with current. However, when the form shown in Figure 5 is used no current can be secured except what passes through the meter 4 unless some part of the device is broken.

I claim:

1. A device of the character described including a switch having a pair of fuse boxes, said switch comprising a casing having an annular socket, a disc shaped switch body rotatably fitted into said socket, a journal member having one end countersunk in said body, and the other end screwed into the back of said body, said body having a pair of sockets at spaced points, a lock carried by said body having a bolt adapted to be thrust into either of said sockets, the lock in the body being in either of two positions, and a pair of switch structures arranged at diametrically opposite sides of said body, part of said switch structure being carried by the body and part by the casing, said switch structures being in functioning position when said bolt is in one of said sockets, and in nonfunctioning position when the bolt is in the other socket, and electrical conductors connecting the respective switch structures, said conductors including a fuse box in each conductor.

2. A device of the character described including a switch structure, said structure having a casing and a rotatable switch body, a pair of spaced contacts on diametrically opposite sides of said body, conductors carried by said body and forming part of two circuits, said conductors being connected at the respective ends to certain of said contact plates, a fuse arranged in each of said conductors, means for rotatably mounting said body in said casing, and means for locking said body in either of two positions.

3. In a device of the character described a switch having a casing formed with a central bore having a pair of spaced radial sockets, a switch body positioned in said bore and carrying contact plates, contacts carried by said casing, said body being rotatable so as to move said plates into and out of engagement with said contacts, a lock carried by said body provided with a bolt adapted to be inserted into either of said sockets for locking said body in a position with the contact plates in or out of engagement with said contacts, and a pair of conductors connected to said respective plates, said conductors being embedded in said body with a fuse interposed in each conductor.

WILLIAM M. MITCHELL.
